Patented June 11, 1968

211,327

VINYL COVERED METAL STEP TREAD

Leib Karpfen, 34 Nassau St.,
Elmont, N.Y. 11003

Filed Oct. 12, 1967, Ser. No. 8,969

Term of patent 14 years

(Cl. D13—7)

FIGURE 1 is a perspective view of my vinyl covered metal step tread embodying the features of my new design,

FIG. 2 is a top plan view thereof,

FIG. 3 is an end elevational view taken on line 3—3 of FIG. 1,

FIG. 4 is a top perspective view of a vinyl covered metal step tread showing a modified form of my new design,

FIG. 5 is a top plan view thereof, and

FIG. 6 is an end elevational view taken on line 6—6 of FIG. 5.

I claim:

The ornamental design for a vinyl covered metal step tread, substantially as shown and described.
